UNITED STATES PATENT OFFICE

PETER A. PETERSON, OF CHICAGO, ILLINOIS

COMBINATION THERMOSTATIC SWITCH AND PLUG CONNECTER

Application filed April 25, 1928. Serial No. 272,616.

My invention relates, generally, to heat-controlling devices for electric irons, hot plates, electric percolators, and similar electrically-heated devices.

5 It is an object of my invention to provide improved means for controlling the electric circuit to an electrically-heated device.

A further object is to provide a device 10 of this kind which forms a part of the connecting socket and may readily be used with any heating appliance.

A further object is to provide a device 15 of this kind in which the temperature at which the device is to be maintained may readily be adjusted.

A further object is to provide an improved device of this type which will save electric current and prevent fires and accidents due to overheating of the electric 20 appliance to which it is attached.

A further object is to provide an improved thermally-controlled switch which is simple in construction, may be economically manufactured and which is efficient in operation.

25 Other objects will appear from the following description, reference being had to the accompanying drawings, in which

Fig. 1 is an elevation of an electric iron with my improved combination connecting 30 socket and thermostatic switch applied thereto;

Fig. 2 is a side elevation of my improved 35 thermostatic switch and connecting socket;

Fig. 3 is a longitudinal sectional view 40 thereof taken on the line 3—3 of Fig. 2; and

Fig. 4 is a sectional view taken on the line 4—4 of Fig. 3.

In the past, electric irons and similar 45 appliances have been equipped with thermostatically-controlled switches but these switches have always been incorporated as a part of the iron itself and are therefore relatively inaccessible for repair or replacement. I have therefore provided a novel form of thermostatic control switch which is incorporated as part of the socket used to make the electrical connection to the iron.

50 In Fig. 1, I have shown the conventional

electric iron 6 as having a pair of connecting prongs 8 over which a plug socket connector 10 is fitted. The connector comprises a pair of body portions 12 and 14 which are secured together by bolts 16 and 18 which 55 pass through the body portions and whose heads and nuts fit in suitable recesses 20 formed in the body portions 12 and 14.

An electric current is conducted to the connector 10 through a pair of conductors 22 which are protected by a coil spring 24, the end of the latter being held in a suitable groove 26 formed in the portions 12 and 14. The ends of the conductors are secured to the portion 12 by screws 28 and 30 which are threaded in suitable nuts 32. These nuts are preferably firmly imbedded in the portion 12. The screw 30 holds the end of one of the conductors in electrical contact with a connecting bar 34, the other end of which is eyelet riveted to a pair of resilient members 36 which together form a suitable spring socket for the reception of one of the prongs 8.

A similar socket for the other prong 8 is provided by a pair of resilient members 38. These members are secured with a bimetallic thermostatic element 40 to the body portion 12 by a screw 42 which is threaded in a nut 44, the latter being imbedded in 50 the body portion 12. The other end of the thermostatic element 40 carries a suitable tungsten or platinum contact point 46 which is adapted to make an electric connection with a similar contact point 48 secured to the end of a screw 50 which is threaded in a support 52. The end of the screw has a knob 54 of insulating material and has a pointer 56 attached thereto. This pointer cooperates with an indicating dial 58 formed 55 upon the surface of the body portion 14.

The body portion 14 has a suitable aperture 60 to receive a portion of the support 52 and to permit the screw 50 to be threaded into the support. A stop pin 62 60 is set in the body portion 14 and adapted to be engaged by the pointer 56 and thus limit rotative movement of the screw 50.

The support 52 is held in place by the screw 65 100 28 and is, of course, of conducting material

so as to transmit the electrical current from one of the conductors 22 to the contact point 48.

The thermostatic element 40 may be made of any two suitable metals having sufficiently different coefficients of expansion.

In operation, the connector 10 is pushed over the prongs 8 in the usual manner and the current is thus supplied to the iron through one of the conductors 22, support 52, contact points 48 and 46, thermostatic element 40, and socket members 38. The return circuit is through the socket members 36, bar 34 and the other conductor 22. As the iron heats up to a predetermined temperature, the thermostatic element 40 will be heated through conduction of heat through the prong 8 and socket member 38. The electrical resistance of the thermostatic element 40 is insufficient appreciably to affect its temperature when the connector is used with the usual appliances drawing a relatively low amperage current.

As the element 40 becomes heated it bends away from the position shown in full lines in Fig. 3 to the position shown in dotted lines in said figure, thereby breaking the electrical circuit to the iron. As the temperature of the iron again drops, the temperature of the element 40 will be correspondingly lowered and at a predetermined temperature will again bend back to the position shown in full lines in Fig. 3 and close the circuit to the iron.

The temperature at which the electrical circuit is opened and closed may be varied by adjusting the screw 50. By turning the screw clockwise (Fig. 2) the contact point 48 will be moved to the left (Fig. 3) and thus it will require a higher temperature to cause the element 40 to bend sufficiently to open the circuit.

When the screw is turned counterclockwise to the position where its pointer abuts against the stop 62, the contact points 46 and 48 will be separated, thereby interrupting the circuit to the iron irrespective of the temperature of the latter.

When it is desired to use the connector with an appliance which requires an unusually high voltage and amperage current, a suitable quick snap-over mechanism may be incorporated in the device to cause sudden separation of the contact points. However, in normal use, such mechanism is unnecessary.

The invention is capable of wide variation within equivalent limits and I contemplate such variation as may be desirable or useful in the particular adaptation of the invention shown, or in its adaptation to other devices.

I do not restrict myself in any unessential particulars, but what I claim and desire to secure by Letters Patent is:

1. In an electric plug socket connector for electric heating appliances, the combination of a pair of insulating body members secured together, a pair of sockets adapted to receive

the connection prongs of a heating appliance and transmit electric current thereto and heat therefrom, each of said sockets being formed in two halves, a bimetallic thermostatic element having one end positioned between the ends of the halves of one of said sockets and extending longitudinally of said body members, a screw for fastening said socket halves and said element to one of said members, a substantially Z-shaped support secured to said last-named member and having a portion overlying the free end of said thermostatic element, and a screw threaded in said portion of said support and having a point for contact with the free end of said thermostatic element, said screw extending through an opening in the opposite body member and having a manually engageable finger piece for adjustment of the position of the contact point thereof.

2. In an electric plug socket connector for electric heating appliances, the combination of an insulating body member, a metallic plug receiving socket formed in two halves secured within said body member, a bimetallic thermostatic element secured between the halves of said socket and in electrical and heat conducting contact therewith, a support secured within said body and having a portion overlying the free end of said thermostatic element and projecting partially through an aperture in said body, a contact screw threaded in said portion of said support extending outwardly through said aperture and having a manually engageable insulating head thereon, and non-fusible contact points, one secured to the free end of said thermostatic element and the other to the end of said screw.

In witness whereof, I hereunto subscribe my name this 21st day of April, 1928.

PETER A. PETERSON.
